(57) **CLAIM**

The ornamental design for a tank securing device, as shown and described.

DESCRIPTION

FIG. 1 is a front perspective view of a new design for a tank securing device.

FIG. 2 is a front view of a new design for a tank securing device.

FIG. 3 is a rear view of a new design for a tank securing device.

FIG. 4 is a left side view of a new design for a tank securing device.

FIG. 5 is a right side view of a new design for a tank securing device.

FIG. 6 is a top view of a new design for a tank securing device; and,

FIG. 7 is a bottom view of a new design for a tank securing device.

The broken lines in the drawings illustrate portions of the tank securing device that form no part of the claimed design.
